US00D839444S

(12) **United States Design Patent** (10) Patent No.: **US D839,444 S**
(45) Date of Patent: ** Jan. 29, 2019

(54) **CRUCIBLE**

- (71) Applicant: **A.L.M.T. Corp.**, Tokyo (JP)
- (72) Inventors: **Yoshitake Fukaya**, Toyama (JP); **Masahiro Kato**, Toyama (JP); **Makoto Watanabe**, Toyama (JP); **Kiyohide Sasaki**, Tokyo (JP)
- (73) Assignee: **A.L.M.T. CORP.**, Tokyo (JP)
- (**) Term: **15 Years**
- (21) Appl. No.: **29/543,974**
- (22) Filed: **Oct. 29, 2015**

(57) CLAIM

The ornamental design for a crucible, as shown and described.

DESCRIPTION

FIG. 1 is a front view of a crucible showing our design; FIG. 2 is a rear view thereof; FIG. 3 is a top plan view thereof; FIG. 4 is a bottom plan view thereof; FIG. 5 is a right side view thereof; FIG. 6 is a left side view thereof; FIG. 7 is a cross-sectional view taken along line 7-7 of FIG. 3 thereof; and, FIG. 8 is a perspective view thereof. In the drawings the broken lines are for the purpose of illustrating environment only and form no part of the claimed design.
